PC; Jinggao Li, Esq.

(57) **CLAIM**

The ornamental design for a seat, as shown and described.

DESCRIPTION

FIG. 1 is a front perspective view of a seat showing my new design;

FIG. 2 is a rear perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof; and

FIG. 8 is a bottom plan view thereof;

FIG. 9 is an enlarged view of the selected portion 9 in FIG. 1;

FIG. 10 is an enlarged view of the selected portion 10 in FIG. 1;

FIG. 11 is an enlarged view of the selected portion 11 in FIG. 2;

FIG. 12 is an enlarged view of the selected portion 12 in FIG. 3; and,

FIG. 13 is an enlarged view of the selected portion 13 in FIG. 7.

The broken lines are for environmental proposes only and form no part of the claimed design.

1 Claim, 13 Drawing Sheets
